UNITED STATES PATENT OFFICE.

JOHN VAN GEEM, OF ERIE, PENNSYLVANIA, ASSIGNOR OF ONE-HALF TO DELMAR VAN GEEM, OF ERIE, PENNSYLVANIA.

BOTTLE CRATE.

Application filed July 29, 1926. Serial No. 125,639.

Among the features of this invention is the improvement in the bottom support for a bottle crate. In the present invention this is formed of sheet metal plates in connection 5 with rods extending along the plates. The invention also contemplates an improvement in the arrangement of the rods and also in the re-enforcing scheme for the bottom strip of the crate. Other features and details of the 10 invention will appear from the specification and claims.

The invention is illustrated in the accompanying drawings as follows:—

Fig. 1 shows a perspective view of the 15 crate, partly broken away to better show construction.

Fig. 2 a section on the line 2—2 in Fig. 1.

Fig. 3 a section on the line 3—3 in Fig. 1.

Fig. 4 a plan view of one of the bottom 20 plates.

Fig. 5 a section on the line 5—5 in Fig. 4.

The crate has the ends 1 and sides 2. The ends are made up of strips 3, the sides of strips 4 with a bottom strip 5. The bottom 25 strip has a re-enforcing plate 6 along its bottom edge which extends around the end of the strip and has a return end 7 extending between the superimposed strip 4 and the strip 5. A nail, or screw 8 extends through the re- 30 enforcing plate 6 and the return end and into the strip 4 next above the strip 5.

Bottom supporting plates 10 extend across the crate and into the space directly above the bottom strip 5. The edges of this plate 35 are bent down forming flanges 11 strengthening the plate and the plates also have perforations 12 extending through the center which are surrounded by webs 13. The effect is to form channels along each edge of the plate 40 in which are arranged rods 14. These rods have their ends 15 bent at right angles to the body of the rod and these extend through perforations 16 in the ends of the plates and into perforations 17 in the strips 4, the perforations opening into the space between the strips. The strip 5 is grooved to permit the entrance of the rod. By this construction the rod braces the plate and locks the walls of 45 the crate against spreading, or collapsing.

These walls are subjected to very severe 50 strains, the inward strains being equal to the outwardly extending strains. The combined plate and rod structure braces it as to this. Further the rods extending through the 55 perforations in the plates and then into the strips makes a secure connection between the

plates and the strips which braces the crate against diagonal strains.

Division plates 19 are in the form of small strips and these are secured by nails 20 on the 60 tops of the strips 3 and 4. At the top I provide a series of cross rods 21 and lengthwise rods 22. These rods all have the turned ends 23 and a center rod 24 extending across the 65 crate is arranged under the rods 22. The end cross rods are above the rods 22. The center rod is also looped at 25 at its crossings with the rods 22 so as to retain the rods 22 in position. This center cross rod is utilized in the handling of the crates as a handle, the 70 operator grasping this center rod and lifting the crate with it. By placing this center rod under the endwise rods and looping it, it readily sustains this strain particularly when provided with the turned ends which extend 75 into the sockets in the strip.

What I claim as new is:—

1. In a bottle crate, the combination of a 80 crate wall having wall strips with perforations opening from the edge of said strips; bottom plates having perforated ends extending over wall strips; and rods extending along the plates and at an angle to the body of the rods through the perforations in the plates and into the perforations in the adjacent 85 strips.

2. In a bottle crate, the combination of a 90 crate wall having wall strips with perforations opening from the edge of said strips; bottom plates having perforated ends extending over wall strips, said plates being formed with longitudinal channels between the walls; and rods extending along the channels in the plates and at an angle to the body of the rods through the perforations in 95 the plates and into the perforations in the adjacent strips.

3. In a bottle crate, the combination of a 100 crate wall having wall strips with perforations opening from the edge of said strips; bottom plates having perforated ends extending over wall strips and formed with longitudinal side webs along their intermediate portions and longitudinally extending perforations surrounded by webs; and rods 105 arranged adjacent to the side webs and at an angle to the perforations in the plates into the perforations in the adjacent strips.

In testimony whereof I have hereunto set my hand.

JOHN VAN GEEM.
